Walnut Kylie 3 Drawer Chest by Kirklands, first available: Aug. 8, 2019. Kirklands.com [online], [site visited Apr. 20, 2022], Internet URL: <https://www.kirklands.com/product/Furniture/Bedroom-Furniture/Dressers-Chests/Walnut-Kylie-3-Drawer-Chest/pc/2285/c/3059/sc/2419/227303.uts> (Year: 2019).*

Primary Examiner — Steven J Czyz*Assistant Examiner* — Hillary Catherine Shepard(74) Attorney, Agent, or Firm — Workman Nydegger(57) CLAIM

The ornamental design for a chest, as shown and described.

DESCRIPTION

FIG. 1 is a front perspective view of a chest showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof; and,

FIG. 7 is a left elevation view thereof.

The broken lines in the drawings are for the purpose of illustrating portions of the article that form no part of the claimed design.

1 Claim, 4 Drawing Sheets(56)
